UNITED STATES PATENT OFFICE

164,649

BAND SAW

William Ferdinand Ocenasek, Plainfield, N. J.

Application October 9, 1950, Serial No. 12,490

Term of patent 14 years

(Cl. D93—3)

To all whom it may concern:

Be it known that I, William Ferdinand Ocenasek, a citizen of the United States, residing in Plainfield, in the county of Middlesex and State of New Jersey, have invented a new, original, and ornamental Design for a Band Saw, of which the following is a specification, reference being had to the accompanying drawing, forming a part thereof.

Figure 1 is a left side perspective view of a band saw, embodying my new design;

Figure 2 is a right side perspective view of the band saw shown in Figure 1;

Figure 3 is a front perspective view of the band saw shown in Figure 1; and,

Figure 4 is a rear perspective view of the band saw shown in Fig. 1.

I claim:

The ornamental design for a band saw, substantially as shown.

WILLIAM FERDINAND OCENASEK.
